UNITED STATES PATENT OFFICE

HARRY A. WINTERMUTE, OF NEW YORK, N. Y., AND CARL W. J. HEDBERG, OF MIDDLESEX BOROUGH, NEW JERSEY, ASSIGNEES TO RESEARCH CORPORATION, OF NEW YORK, N. Y., A CORPORATION OF NEW YORK

ELECTRICAL PRECIPITATOR CONSTRUCTION

Application filed June 12, 1928. Serial No. 115,642.

This invention relates to electrical precipitators of the high resistance or low conductivity electrode type.

It is an object of this invention to provide an electric precipitator of the type referred to which is easy to make and assemble and relatively cheap to manufacture.

Another object is a precipitator which can be quickly repaired and at low cost.

Another object is a treater which may be readily and effectively cleaned.

The objects referred to and other objects will more clearly appear in connection with the accompanying drawings in which

Figs. 1, 3 and 5 are elevations of different forms of collecting electrodes embodying the invention;

Figs. 2, 4 and 6 are plan views thereof;

Fig. 7 is a diagrammatic plan view of a simple application of the invention;

Fig. 8 is a sectional view of a special form of treater embodying the invention; and

Fig. 9 is a diagrammatic plan view on an enlarged scale of a part of the construction shown in Fig. 8, explaining the essential features of operation.

Fig. 10 shows a modified arrangement of the unit electrodes.

Figs. 11, 12, 13 and 14 show modifications of various types of electrodes.

The present invention, as to the general principle of operation, is similar to the electrical precipitator disclosed in the patent to Anderson, No. 1,541,677, but materially differs therefrom in that the collecting electrodes are composed of unit elements placed in juxtaposition or in any desired spaced relation.

Such unit elements are illustrated in Figs. 1-6. Each element consists of an elongated body of relatively high resistant material. As indicated in Figs. 1 and 2, this body 10 may be of circular cross-section, i. e. may be a cylinder. As indicated in Figs. 3 and 4, the body 11 may be polygonal, rectangular or square in particular. As indicated in Figs. 5 and 6 the cross-section of the body 12 may be elliptical or oval in general. Figs. 11, 12, 13 and 14 show other cross sectional shapes of electrodes which may be used such as

Y 25, star 26, channel 27 or angle 28. These forms merely illustrate what we consider as the preferred embodiments within the scope of the invention.

The bodies 10, 11 and 12 or other similar elongated bodies preferably contain embedded therein a conductor 13 occupying the central or axial position. While the provision of a conductor is generally preferable, the invention may be carried out without it, or conductors may extend only part way through the bodies of resistance material.

There is great latitude in regard to the characteristics of the relatively high resistant material itself, which, for instance may be concrete, ceramic material, or material of that kind mixed with carbon or other suitable material to impart to the mixture a definite degree of conductivity.

The bodies 10, 11 and 12 might consist of layers of materials with different characteristics of resistance, expansion, etc. Finally, the bodies might consist of shells of the desired material filled with gas, oil or other suitable liquid.

The principle direct advantage that may be derived from the unit collecting electrode element is the possibility of building up a collecting electrode or a collecting electrode system of any form, of individual units, whereby the manufacture of the electrode system is materially simplified. The parts may be easily assembled, and readily exchanged for the purposes of repair without requiring an extended shut-down of the treater.

Fig. 7 illustrates a collecting electrode system built up by means of unit elements according to this invention. The cylindrical unit elements 15 containing conductors 15^a are disposed in parallel relation in straight rows between which are placed in the usual way the discharge electrodes 16. There may be, of course, any number of rows and the spacing is a matter of judgment depending on particular conditions.

One additional advantage incident to the invention is the facility with which the collecting electrode surface may be cleaned. Inasmuch as each unit is relatively small and independent, it can be effectively rapped

to remove the deposit. The rapping may be done at either end, as is well understood in the art.

Similarly this construction facilitates effective cleaning by other methods. For example, each unit can be rotated about its long axis while its surface is in contact with the surfaces of adjacent units, or with a fixed and independent knife edge. Moving one extremity, in a plane, parallel to the longitudinal axis of all adjacent units, about the other extremity as a center will loosen and dislodge adhering deposits bridged between adjacent units in the construction shown in Figure 9. The construction also lends itself to cleaning by means of an automatic scraping device similar in principle to that used for cleaning tubes in fuel economizers.

There are many ways in which the invention may be applied. The unit elements may be placed vertically or horizontally or in any other position. The discharge electrodes may extend parallel or at an angle to the unit elements. There is no definite limit in this respect. Instead of forming straight rows, the unit elements may be correlated to define curved rows.

Aside from the advantage of general flexibility of construction, the invention may find special application as, for instance, shown in Figs. 8 and 9.

In Fig. 8 is illustrated a horizontal flow treater in which the gases enter through the inlet 21 of the casing 20 and pass out through the outlet 22. The collecting electrodes are composed of unit elements 23 forming a plurality of rows transversely of the gas stream. In the particular construction, there are a plurality of groups of two rows each. The unit elements 23 in the two rows of each group are in staggered relation as shown in Fig. 9. The discharge electrodes 24 are so placed that each has the same discharge position relatively to two unit elements 23 of a row.

The general object of this arrangement is to combine electrical precipitation and mechanical separation to give a maximum cleaning effect. The unit elements 23 of each row define a plurality of constricted passages through which the gas must flow and due to the staggered relation of the rows, the gas passages form an alternately constricted and expanded path. The discharge electrodes 24 are so placed relatively to the collecting electrode unit elements that the corona discharge is directed substantially at right angle to the gas flow.

The relative positioning of the collecting unit elements, the tortuous path and the alternate expansions and contractions are instrumental in producing a mechanical cleaning effect, which is supplemented by the electrical precipitating action.

65 The corona discharge so named because it

is luminous, subjects the gases to a strong electric field and brings about intense ionization which accomplishes a two-fold purpose. It tends to precipitate the fume dust, etc. upon the collecting electrode surfaces and also to agglomerate the minute particles, which if not precipitated directly, are mechanically intercepted by the electrodes 23 and thus removed from the gas stream by gravity action. In Fig. 10 we have shown a modified arrangement of unit element 23, wherein alternate ones do not contain conducting elements 13. Discharge electrodes 24 are shown as arranged between two unit electrode containing conductors 13. However, in dotted lines we have shown an alternate position for these electrodes.

It is understood that also in this embodiment of the invention, the electrode unit elements 23 may have various forms, such as indicated in Figs. 1-6 and Figs. 11-14.

We claim:

1. In an electrical precipitator, the combination with two spaced discharge electrode systems of a collecting electrode system composed of a plurality of spaced unit elements, each of said elements comprising a central conductor and a body of relatively high resistant material surrounding the same.

2. In an electrical precipitator, the combination with two spaced discharge electrode systems of a collecting electrode system composed of a plurality of spaced unit elements, each of said elements comprising a central conductor and a body of relatively high resistant material of substantially uniform cross-section surrounding the same.

3. In an electrical precipitator, a collecting electrode system composed of a plurality of unit elements, said unit elements being spaced apart longitudinally of and transversely of the direction of gas flow and each of said elements comprising a central conductor and a body of relatively high resistant material of substantially uniform cross-section surrounding the same, the body of material having a diameter considerably in excess of the thickness of the conductor.

4. In an electrical precipitator, the combination of a collecting electrode system composed of a plurality of unit electrodes presenting peripheral surfaces of relatively high resistant material, said electrodes being disposed in spaced relation and disposed to define alternately contracted and expanded gas passages, and a series of discharge electrodes so positioned with respect to said unit electrodes that the corona discharge from said discharge electrodes takes place across contracted portions of said gas passages and extends to only a limited part of the surface area of the relatively high resistant material of said unit electrodes.

5. A construction according to claim 4, wherein the unit elements are disposed in a

plurality of rows and the unit elements of one row are displaced relatively to the unit elements in another row.

6. A construction according to claim 4, 5 wherein the unit elements are disposed in a plurality of rows and the unit elements of one row are disposed on lines midway between adjacent unit elements in an adjacent row.

7. In an electrical precipitator, the combination of a collecting electrode system composed of a plurality of unit elements presenting peripheral surfaces of relatively high 10 resistant material, said elements being disposed in spaced relation longitudinally of 15 and transversely of the direction of gas flow to define alternately contracted and expanded gas passages, and discharge electrodes, each discharge electrode having a symmetrical discharge relation to two adjacent unit elements 20 in a row.

8. In an electrical precipitator, the combination of a collecting electrode system composed of a plurality of unit elements presenting peripheral surfaces of relatively high 25 resistant material, the unit elements being disposed to form a plurality of groups of two parallel rows each wherein the unit elements in one row are laterally offset relatively to the unit elements of the other row, each group 30 being spaced from the adjacent group a greater distance than the distance between the rows of the same group, and discharge electrodes disposed between the groups so 35 that each pair of adjacent unit elements in a row has substantially the same relation to one discharge electrode.

9. In an electrical precipitator, a collector electrode system defining a gas passage having zones of high and of low gas velocity, and 40 discharge electrodes; said collector electrode system comprising collecting electrodes of high resistance material presenting only limited surface areas to said discharge electrodes to provide an electrostatic field in and 45 of varying intensity along said gas passage, and said discharge electrodes being so positioned that zones of high field intensity are located at zones of high gas velocity.

10. The invention as set forth in claim 9, 50 wherein said collector electrode system comprises unit elements spaced longitudinally of and transversely of the line of gas travel, each of said elements being an elongated body presenting a peripheral surface of resistance material.

In testimony whereof, we affix our signatures.

HARRY A. WINTERMUTE.
